UNITED STATES PATENT OFFICE.

FREDERICK W. WHITEHOUSE, OF BROOKLYN, NEW YORK, ASSIGNOR TO
THE TIFFANY & COMPANY, OF NEW YORK, N.Y.

DESIGN FOR A BADGE.

SPECIFICATION forming part of Design No. 27,201, dated June 15, 1897.

Application filed March 31, 1897. Serial No. 630,182. Term of patent 7 years.

To all whom it may concern:

Be it known that I, FREDERICK W. WHITEHOUSE, of Brooklyn, in the county of Kings and State of New York, have invented and produced a new and original Design for a Badge, of which the following is a full, clear, and exact description, reference being had to the accompanying drawing, forming a part of this specification.

10 The drawing shows a face view of the design, which consists of a conventional representation of the national tomb or monument of General Ulysses S. Grant, having upon the front thereof a portrait of General Grant, said

design bearing palm-like fronds or branches 15 twined with ribbon-like ornamentation, presenting panels for suitable words or dates.

I claim—

The design for a badge substantially as herein shown and described. 20

In testimony whereof I have signed my name to this specification in the presence of two subscribing witnesses.

F. W. WHITEHOUSE.
